Inventor:
Peter H. McKenzie,

By Sheridan Jones, Sheridan & Smith.

attys.

UNITED STATES PATENT OFFICE.

PETER H. MCKENZIE, OF CHICAGO, ILLINOIS.

FURNACE CONSTRUCTION.

Application filed August 9, 1920. Serial No. 402,479.

To all whom it may concern:

Be it known that I, PETER H. MCKENZIE, a citizen of the United States, residing at Chicago, in the county of Cook and State of Illinois, have invented certain new and useful Improvements in Furnace Construction, of which the following is a specification.

This invention relates to improvements in furnace construction and has for its object 10 to provide a new and improved means for creating a natural or forced draft for a chain grate stoker. In the embodiment of my invention shown in the accompanying drawings, I provide a plurality of separately controlled air ducts just beneath the upper path of travel of the chain grate and closely adjacent thereto. I am thereby enabled to apply the draft properly through the entire bed of fuel and to regulate the 15 same, if desired, at various sections of the fuel bed, in accordance with existing conditions. In present day construction, it is the practice to supply the air for combustion either by forced or natural draft to the entire body of fuel as a unit with the result 20 that the fuel bed becomes burned out, or holes, as they are termed, are formed therein through which the air will rush seriously interfering with the proper function of the 25 furnace.

Other objects of my invention consist in the provision of means for the control of draft through the conduit members, and the provision of means to permit ready cleaning 30 thereof. These and other objects will be more fully described and set forth in the following specification and shown in the accompanying drawings, in which—

Fig. 1 is a side elevation of a detail of an 40 embodiment of my invention, a portion of the draft chamber thereof being broken away for clearness;

Fig. 2 is a vertical transverse section along the line 2—2 of Fig. 1;

Fig. 3 is vertical longitudinal section of a detail taken along the line 3—3 of Fig. 2; and,

Fig. 4 is a plan view of a portion of the mechanism showing a portion thereof as 50 broken away for clearness.

Like numerals refer to like elements throughout the drawings in which—

10 indicates generally an endless chain grate stoker formed, for example, of the 55 usual links 10^a carried upon the rods or shafts 11 (see Figs. 2 and 3), suitable draft

apertures or passages 10^b being provided between adjacent links to permit access for the air for combustion to and through the fuel body. The chain grate mechanism is supported by and travels upon the rollers 13 spaced apart, as shown in Fig. 3 for example, it being well known to those skilled in the art that the under or returning portion of the chain grate is also suitably supported upon similar rollers 13 which engage those faces of the links which support the fuel during their travel in the upper orbit.

Located between spaced apart rollers 13 are the draft boxes 15, shown as provided with the arched upper walls 15^a, perforated at 15^b, these perforated walls being located just beneath the path of travel of the chain grate links so as not to be contacted thereby. At one end each of the boxes 15 is in communication with a draft chamber 16, being secured thereto by suitable clamping plates 17 and bolts and nuts 18, see Fig. 2 for example, the draft boxes being flanged at 15^c to permit such clamping.

The draft chamber 16 is tapered from the front of the furnace toward its closed end 16^a, see Fig. 1 for example. At its other end 16^b, this chamber 16 is secured to the air duct or elbow 16', provided with a butterfly valve 85 or damper A, controlled by the rod 19 and arm 18^a. This duct 16' is in communication with conduit 20, which in turn communicates with a centrifugal fan or other suitable air circulating means not shown, such fan 90 being available to force air through duct 16' and therefrom to air chamber 16.

A sliding gate or valve 21 is provided for each of the draft boxes 15 at the juncture thereof with the draft chambers 16, these 95 doors sliding between flanges 21^a and the side walls 16^c of the draft chamber 16, see Fig. 2. Suitable spacing strips 22 serve to properly space the plates 21^a from the side wall 16^c, the bolts serving to also maintain 100 these members in proper relation. Each of the doors is provided with an angle member 24, the outwardly extending flange 24^a thereof being engaged by the threaded end 25^a of the operating rod 25 which is secured thereto 105 by nuts 26, or the like, see Figs. 2 and 4 for example. The innermost of the rods 25 is substantially straight throughout its length, the remaining rods being parallel therewith and having their inner ends bent inwardly 110 adjacent their engagement with the respective gates or valves 21. The engageable ends

25^b of the rods 25 project outwardly through the elbow 17, see Fig. 1 for example. It will be apparent that each of the gates 21 may be adjusted, as desired, to regulate the draft 5 through the boxes 15. The draft chamber 16, as stated, is tapered to compensate for the gradually decreasing volume of air flowing through the same.

At their opposite ends the boxes 15 are 10 provided with doors 30 similar to the valves or gates 21 and similarly controlled by rods 31 to permit inspection or cleaning out of the boxes when desired. The draft chamber 15, see Fig. 2, for the purpose of inspection and cleaning.

By the mechanism described above, it is possible to regulate the draft, either forced or natural, as desired, at various points 20 beneath the fuel bed and, should the fire become thin and holes occur in any section of the bed, all of the draft air will not rush therethrough but merely a small portion thereof so that the draft to the balance of 25 the fuel bed is substantially unimpaired. Also as will be obvious, should one section of the bed require more or less draft, it may be accommodated by a proper manipulation of the valves and operating rods. A further advantage consists in the delivering 30 of the air draft directly beneath the fuel bed in such wise as to insure its passage through the bed without the establishing of any short circuit as in present day construction, thus eliminating the necessity for seals 35 at the ash delivery end of the grate. When forced draft is used, air under pressure is delivered to the boxes 15 by a fan or pump or other suitable means. At times, however, the pressure may be discontinued and 40 the air drawn through the line by natural draft.

It will be obvious that my invention is susceptible to numerous modifications and 45 improvements and I do not wish to be restricted to the form shown except as defined in the appended claims.

What I claim is:—

1. In combination with a movable fuel

supporting means, a plurality of air ducts 50 located transversely therebeneath, and spaced apart to permit of natural draft therebetween, the upper surfaces of said ducts being perforated and located closely adjacent said supporting means, means to supply air under pressure to said ducts, and means to regulate or cut off said pressure supply.

2. In combination with a movable fuel-supporting means, a plurality of air supply 60 ducts located transversely therebeneath, the upper surfaces of said ducts being perforated and located closely adjacent said supporting means, and said ducts being spaced to permit natural draft therebetween.

3. In combination with a movable fuel-supporting means, a plurality of air ducts located transversely therebeneath and spaced apart to permit of natural draft therebetween, the upper surfaces of said 70 ducts being perforated and located closely adjacent said supporting means, means to supply air under pressure at said ducts, and means to regulate or cut off said pressure supply, the said upper surfaces of said ducts being arched to expose substantially the entire area of fuel carried by said supporting means to the natural draft in the event said pressure supply is cut off.

4. In combination with a movable fuel-supporting means, a plurality of air supply ducts located transversely therebeneath, the upper surfaces of said ducts being perforated and located closely adjacent said supporting means, and means to supply air 80 under pressure to said ducts, said means comprising a duct extending longitudinally of said supporting means at one side of the latter and communicating with each of said first-named ducts, said longitudinally extending duct being tapered and of largest cross-sectional area at its intake end to 85 compensate for the gradually decreasing volume of air flowing through the same.

In testimony whereof, I have subscribed 90 my name.

PETER H. MCKENZIE.
